UNITED STATES PATENT OFFICE

2,607,060

METHOD OF SECURING A NAVY TYPE BACK-STRAP TO A NAVY TYPE LOW SHOE

John W. Foley, St. Louis, Mo., assignor to International Shoe Company, St. Louis, Mo., a corporation of Delaware

Application August 17, 1949, Serial No. 110,704

2 Claims. (Cl. 12—146)

1
The present invention relates generally to the shoe art, and more particularly to a method of and apparatus for securing a backstrap to a low shoe.

In brief, the present invention contemplates the sequential steps, in the securing to a low shoe of the backstrap, of supporting the rear quarters of a low shoe on a surface having a form complementary to the predetermined contour of the back portion of the rear quarters, applying a strong leather type cement to a backstrap, and accurately securing it in its intended position at the back of the rear quarters, permitting the cement to dry for a predetermined period, reversing or turning the rear quarters inside out to dispose the backstrap interiorly, stitching the backstrap to the rear quarters along the side edges with a two-needle machine while the rear quarters are thus turned inside out, and returning the rear quarters with attached backstrap to the normal position for subsequent operations in the formation of the shoe. Novel apparatus for carrying out the foregoing method includes a rear quarters receiving post having an upper end contoured to receive a rear quarters, a rear quarters hold-down device for maintaining the rear quarters in position on the post, and a pivotal mount for the unit which facilitates the mounting of the rear quarters on the post and the subsequent cementing thereto of navy backstrap.

The invention has particular application in overcoming the deficiencies existing in the present day method of and apparatus for applying the conventional navy backstrap to navy low shoes. Mass production methods of attaching the navy backstrap to the rear of the rear quarters have been generally unsatisfactory, particularly in including too much fullness at the top of the backstrap where the required double seam sewing is accomplished by the single-needle machine.

Therefore, an object of the present invention is to provide a novel method of securing a navy backstrap to the rear quarters of a navy low shoe which overcomes deficiencies existing in methods heretofore used.

Another object is to provide novel apparatus for supporting a rear quarters unit of a low shoe while the backstrap is initially applied and secured in position.

Another object is to provide a novel method of securing a navy backstrap to the rear quarters which may be employed in the mass production of navy low shoes to achieve a substantially per-

fect relation of the backstrap to the rear quarters in which the backstrap is initially cemented to the rear of solidly supported rear quarters leaving the vertical edges free and is then sewed with a two-needle machine after removing the rear quarters from the support and reversing it.

Another object is to provide novel apparatus which facilitates the accurate application of a navy backstrap to the rear of the rear quarters.

10 Another object is to provide a novel method of securing a backstrap to the rear quarters of a low shoe by which the backstrap is accurately stitched to the rear quarters along the edges with a two-needle machine while initially held to the quarters by cement, and in which the resultant secured relation of the backstrap to the rear quarters is as desired.

20 Another object is to provide novel apparatus facilitating the attachment of a navy backstrap to the rear quarters of a navy low shoe which incorporates pivotal mounting, rendering easy the initial accurate application of the rear quarters to a receiving post and the later application of the backstrap to the rear quarters.

25 Other objects are to provide a novel method of securing a navy backstrap to the rear quarters of a navy low shoe which is simple in performance, which may be economically applied to the mass production of such shoes of high quality and workmanship, which may be easily learned by a shoeworker, and which achieves a superior product in minimum time and at minimum cost which has long been sought in the shoe art.

30 Still further objects are to provide novel apparatus facilitating the attaching to the rear quarters of a navy backstrap which is simple in construction and operation, which may be readily operated by a shoeworker with ease and accuracy with minimum instruction, and which is efficient in its application.

35 The foregoing and other objects and advantages are apparent from the following description taken with the accompanying drawings, in which:

40 **45** Fig. 1 is a side elevational view of a rear quarters support adapted to be used in the application of backstraps to low shoes which incorporates concepts of the present invention;

50 Fig. 2 is an end elevational view thereof, a portion of the supporting table being broken away for illustration of details;

55 Fig. 3 is a plan view thereof, the ends of the hold-down member of the hold-down device being broken away for clarity of detail;

Fig. 4 is a perspective upside down view of con-

ventional navy rear quarters sewed at the abutting rear edges;

Fig. 5 is an upside down view of a conventional navy backstrap;

Fig. 6 is a side elevational view of the support shown in Figs. 1 through 3 tilted forward and with a navy rear quarters securely held in place on the post;

Fig. 7 is a rear view of a navy backstrap with cement applied thereto;

Fig. 8 is a fragmentary view of the construction shown in Fig. 6, the navy backstrap of Fig. 7 being illustrated as glued to the navy rear quarters;

Fig. 9 is an upside down view of the rear quarters of Fig. 4 with the backstrap of Fig. 7 cemented thereto and sewed along the sides with a double stitch;

Fig. 10 is a view of the assembly of Fig. 9 folded into a normal position; and

Fig. 11 is an enlarged fragmentary horizontal cross-sectional view on substantially the line 11-11 of Fig. 10.

Referring to the drawings more particularly by reference numerals, 18 indicates generally a rear quarters support adapted to be used in the application of backstraps to low shoes, constructed in accordance with the teachings of the present invention, shown mounted on a table 20. Broadly, the support 18 includes a base 22, a rear quarters post 24, a rear quarters hold-down device 26, angle brackets 28, and a biasing tension spring 30.

The base 22 is of rectangular form and is pivotally mounted in spaced relation to the table 20 on the upper ends of the opposed brackets 28 on a bolt 32 secured against removal by a nut 34. Bolts 36 secure the brackets 28 to the table 20.

The rear quarters post 24 is rectangular in cross-section and is secured to the base 22 by screws 38. It includes a rear quarters receiving upper end 40 formed as illustrated to conform to the contours of a received rear quarters of a low shoe. Transverse guide wires 42 and 43, and a longitudinal central guide wire 44 are embedded in the upper end 40 for positioning a rear quarters preparatory to receiving a backstrap.

The rear quarters hold-down device 26 includes an upright member 46 of rectangular cross-section secured to the base 22 by screws 48. A U-shaped rear quarters hold-down member 50 is pivotally supported at its bight from the rear face of the member 46 by a bracket 52. A short arm 54 extends inwardly from one leg of the member 50 and is engaged by a leaf spring 56 secured to the top of the member 46 when the member 50 is elevated as shown in Fig. 1 to hold the member 50 in this raised inoperative position. At the free end of each leg of the member 50 is a resilient ring 58 frictionally mounted on a sleeve 59 secured in place by a washer 60 and nut 62. Operative positions of the member 50 are shown in Fig. 6. It is to be observed from Fig. 2 that the legs of the member 50 will be sprung outwardly when the rings 58 engage a rear quarters disposed on the post 24, insuring maintaining of the rear quarters in place during the application of a backstrap.

The spring 30 is anchored at its lower end to an eye bolt assembly 64 mounted in the table 22 between the angle brackets 28, the upper end engaging a bracket 66 secured to the underside of the base 22 by screws 68. The upper end of the spring 30 slides freely along the bracket 66

to either end thereof to bias the base 22 into position with its forward or left end as viewed in Fig. 6 engaging the table 20, or into position with the rear end engaging the table 20, dependent upon the particular work step being effected of the present novel method of attaching a navy backstrap.

The support 18 is employed in carrying out the instant novel method of attaching a backstrap to a low shoe, a navy rear quarters and backstrap being shown in illustrating the novel method.

A rear quarters unit 70 for a navy low shoe sewed by a usual zigzag lock stitching 72 and having a lining 74 is placed on the post 24 as illustrated in Fig. 6, the conventional cutout at the upper rear center being disposed against the rear guide wire 42 and the stitching 72 being coincident with the longitudinal guide wire 44. The rear quarters unit 70 is held securely in place by the hold-down device 26. Suitable leather type cement 76 is applied to the rear surface of a backstrap 78 preferably along the top edge and centrally forming a T as shown in Fig. 7, and the backstrap 78 is firmly pressed onto the rear quarters unit 70 as shown in Fig. 8 with the upper edge of the backstrap 78 contiguous with the guide wire 43. The cement is permitted to dry, which economically may be around five minutes, whereupon the rear quarters unit 70 with cement applied backstrap 78 is turned inside out and double stitching 80 applied along the outer edges by a regular two-needle machine. The rear quarters unit 70 is returned to normal position, as shown in Fig. 10, and is found to be entirely free of puckering or bunching and it without undesirable fullness at the top of the backstrap. The double stitching 80 is true. The free vertical edges of the backstrap 78 are displaced outwardly just enough when the rear quarters unit 70 is reversed to effect a tight smooth relationship with the rear quarters unit 70 when sewed thus displaced and the rear quarters unit 70 is turned to normal position. No ironing at the heel seat is necessary.

It is manifest that there have been provided a novel method of and apparatus for applying the backstrap to rear quarters of low shoes, particularly applicable to navy oxfords, which fulfill the objects and advantages sought therefor. It is to be understood that the foregoing description and the accompanying drawings have been given by way of illustration and example. It is also to be understood that changes in form of the several parts, substitution of equivalent elements or steps, and rearrangement of parts or steps, which will be readily apparent to one skilled in the art, are contemplated as within the scope of the present invention, which is limited only by the claims which follow.

What is claimed is:

1. In a method of securing a backstrap to rear quarters in the making of a low shoe, the steps of supporting sewed rear quarters in draped relation against a surface of complementary form, cementing a backstrap to the rear quarters while thus draped, removing the rear quarters and attached backstrap and turning the assembly inside out, sewing the backstrap along its vertical edges to the rear quarters with a two-needle machine to provide double stitching, and returning the rear quarters to normal relation with the backstrap on the outside.

2. In a method of securing a backstrap to a rear quarters in the making of a low shoe, the steps of applying cement to the top edge and

centrally of a backstrap, applying the cement containing surface to a rear quarters leaving the vertical edges free, reversing the rear quarters, double stitching the backstrap edges to the rear quarters while thus reversed, and returning the rear quarters and stitched backstrap to normal position.

JOHN W. FOLEY.
